UNITED STATES PATENT OFFICE.

JAMES T. FENTON, OF SALT LAKE CITY, UTAH,

PROCESS OF AND APPARATUS FOR DISTILLING.

1,424,998.

Specification of Letters Patent. Patented Aug. 8, 1922.

Application filed March 29, 1921. Serial No. 456,581.

To all whom it may concern:

Be it known that I, JAMES T. FENTON, a citizen of the United States, residing at Salt Lake City, in the county of Salt Lake and 5 State of Utah, have invented certain new and useful Improvements in Processes of and Apparatus for Distilling, of which the following is a specification.

The present invention particularly relates 10 to a topping still, that is to say, a still adapted for distilling the very light oil fraction, such as gasoline, from mineral oil without producing any cracking, or at least any substantial amount of cracking, of the oil. The 15 objects of the invention are to completely remove the most volatile ingredients from the mineral oil all in one operation, and to do this without depositing any carbon or like material in the still and to so regulate 20 the inflow and outflow as to make the separation complete, while avoiding any overheating, and to accomplish these results in a regular, steady, safe and economical manner.

For the accomplishment of the above objects, the apparatus shown in the annexed drawing is found to give excellent results. In said drawing Figure 1 represents a vertical side elevation, partly in section, of an approved apparatus. Figure 2 represents 25 a view on the line 2—2 looking in the direction of the arrow. Figure 3 represents a front view of a weir and an adjustable gate which co-operates therewith. Figure 4 represents a section taken approximately on the 30 line 4—4 of Figure 3. Figure 5 represents a fragmentary section on the line 5—5 looking downwardly. Figure 6 shows a modified form of construction in vertical section of one of the steps in the distilling process. 35 Figure 7 represents a further modification of the steps of the still.

The operation of the apparatus is as follows: Oil, for example crude mineral oil or 40 preferably crude mineral oil after the sediment has been suitably removed, is introduced through the pipe 10 into a preheater 11, this consisting of a box provided with one or more coils 12, the oil passing downwardly through the coils 12, and steam 45 flowing upwardly through the spaces 14 and the exhaust steam flowing out at 15 (or vice versa, steam in the coil). The oil flows through the pipe 16, provided with an expansion curve 17, and preferably through a 50 by-pass 18 in which is located a butterfly

valve 19, regulated as described below, entering through the nipple 20 into the space 21, below baffle B back of weir 22. The oil overflowing the weir passes downwardly over a series of steps consisting of risers 23 and treads 24 into the well 25. The said well contains a float 26 carried by the rod 27, which rod is rigidly connected to a shaft 28 passing through a stuffing box 29 to a point outside the still. Attached rigidly to 60 the shaft 28 is an arm 30 which in turn is connected to a rod 31, rocker arm 32 (pivoted at 33), rod 34, rocker arm 35 (pivoted at 36) and rod 37 to another rod 38 which operates the butterfly valve 19. The oil outlet from well 25 consists of a pipe 39 which leads the treated oil to a storage tank or to a place for further treatment thereof.

The vapors liberated in the still pass through a reflux vapor outlet pipe 40 past a 75 thermostat 41 located at the upper end thereof, into a series of condenser coils 42 and 43 and the uncondensed gases are drawn off at 44 to be collected for use for any desired process. The condensate is 80 drawn off through the trapped outlets 45 and 46.

The heating of the oil is effected by means of steam entering through pipe 50 and preferably flowing through a by-pass 51 past a 85 valve 52, which valve is controlled by the thermostat 41 through a train of connections 41^a in such a way that the top boiling point of the distillate is maintained constant. The steam enters the space between 90 the steps 23 and 24 and the bottom 53, flowing upwardly therethrough, and the weir 22 is preferably made hollow so that this likewise will be kept full of steam. The steam leaving the upper end of the steam 95 space of the still flows out by the pipe 54 provided with an expansion curve 55, and enters the steam space 14 of the preheater, finally being drawn off at 15. It is understood that suitable drawing-off outlets 56 100 and 57 for water of condensation will be provided.

In distilling the gasoline fraction from crude petroleum the top 58 of the still may be shaped as illustrated in full lines. However, it is preferable, in some cases, to make the left hand end (in Figure 1) square at the top as shown in dotted lines at 59 and 60 (see Fig. 4).

Placed above the weir 22 there is prefer- 110

ably provided an adjustable gate 61 as shown in Figure 3, this being vertically adjustable at each end, by means of the screws 62 and 63; the said screws co-operating with blocks 64 carried by the said gate.

It is advisable that the opening, or slot, between the gate 61 and the weir 22 be of uniform width or height and also that this opening be exactly level. The idea of this opening is to cause the oil being fed into the distilling chamber to spread out uniformly over the steps 23 and 24. The gate is raised or lowered by the screws as above indicated, suitable slides 66 and 67 being provided for this gate.

For the purpose of bringing the top of the weir 22 into a properly horizontal position the still is provided with legs 69, 70, 71 and 72, each of which is provided with a leveling screw. The screws carried by these legs are also capable of regulating the amount of incline of the still itself, and the treads 24 may be thereby caused to slope slightly either forwards or backwards, if desired, or they may be made exactly level.

The lower edge of the gate, as shown in Figure 4, is preferably made beveled to more readily adjust the flow of the oil. The weir 22 may be made hollow as above described for being filled with steam or, in some instances, it is advisable to make this solid, for example of cast iron or the like.

There may be provided in the well 25 a second thermostat device as illustrated at 35 80, this being connected by a train of connections 80^a to a valve 81 in the oil inlet and placed to the right of the valve 19. In case the steam supply should, for any reason, be decreased or cut off this thermostat will close the valve 81 and thereby stop the feed of oil to the device. When the steam is again turned on and the temperature in the well 25 is raised to the proper amount the valve 81 will again open, rendering the process continuous. In this manner any irregularities in the steam supply are readily compensated for in an automatic way.

If it is desired to do so the automatic regulation of the flow of oil and steam may be dispensed with, the oil flowing through the valve 86 in pipe 87, and the steam flowing through valve 88 in pipe 89, these valves being suitably regulated by hand.

The entire heated portions of the apparatus may be provided with a suitable heat insulating covering if desired to prevent loss of heat by radiation.

It will be observed that the film of oil is continuous, and that the same flows over a cascade system or cataract system, the same comprising essentially a highly heated surface, the heating agent being on one side of the metal or other suitable plates forming this heating surface and the oil being on

the other side thereof. It is further to be noted that the heating agent and oil travel in counter-current with each other, whereby the hottest steam is able to impart its heat to the oil which has already been heated to a high degree.

I have above referred to superheated steam as the preferred heating agent. This steam may be at any temperature even up to 1000 F., and may be supplied at any suitable pressures say 5 to 100 pounds more or less. While I have particularly described superheated steam as the preferred heating agent I do not desire to be considered as restricting the invention to the use of this agent since hot gases or vapors (superheated elastic vapors) can be employed in like manner.

I call attention to the fact that when metal plates or sheet metal articles are heated there is always considerable likelihood of some torsion effects produced by the expansion. This may in some instances cause the weir 22 to expand and reduce the space between this weir and the gate 61. This is readily compensated for by raising or lowering the gate. Furthermore the torsion may in some instances cause a slant in the top of the weir. This can readily be compensated for by means of the screw legs 69, 70, 71 and 72 upon which the steel body rests.

The invention has been above described particularly with reference to the apparatus shown in the drawings but I desire it to be understood that the invention embraces also the process of distillation by passing the oil through a continuously flowing cataract still, the heating agent, preferably steam, being supplied and brought into heat-conducting relationship with the oil on the counter-flow principle as above more fully described.

I claim:

1. An apparatus adapted for use as an oil topping still, having a stepped bottom, an oil inlet, an overflow weir adjacent said inlet, and a vertically movable gate over said weir, each end of said gate being vertically adjustable.

2. An oil still comprising a distilling chamber, an oil inlet to said chamber, a transverse weir located near said inlet, a vertically movable gate over said weir, means for adjusting each end of said gate independently, supports for said chamber, and leveling screws cooperating with said supports to bring the top of said weir to a level position.

3. An oil still comprising a distilling chamber having a stepped bottom surface over which the oil flows in a film of substantially uniform depth in one direction, an oil inlet at one end of said chamber, an oil well at the other end of the chamber, means for admitting a heating agent to the

opposite side of said stepped bottom surface so that it will flow in a direction opposite to the flow of oil, and means for controlling the admission of oil to the chamber 5 by the temperature of oil in said well.

4. An oil still comprising a distilling chamber having a stepped bottom surface over which the oil flows in a film of substantially uniform depth in one direction, 10 an oil inlet at one end of said chamber, an oil well at the other end of the chamber, means for admitting a heating agent to the opposite side of said stepped bottom surface so that it will flow in a direction opposite to the flow of oil, and means for controlling the admission of oil to the chamber 15 by the depth of oil in said well.

5. An oil still comprising a distilling chamber having a stepped bottom surface 20 over which the oil flows in a film of substantially uniform depth in one direction, an oil inlet at one end of said chamber, an oil well at the other end of the chamber, means for admitting a heating agent to the opposite side of said stepped bottom surface so that it will flow in a direction opposite to the flow of oil, means for controlling the admission of oil to the chamber by the temperature of the oil in said well, and separate 25 means for controlling the admission of oil to the chamber by the depth of the oil in said well.

6. An oil still comprising a distilling chamber, an oil inlet pipe at one end of said 35 chamber and an oil well at the other end thereof, two valves in said inlet pipe, means governed by the depth of the oil in said well for controlling one of said valves, and means governed by the temperature of the oil in 40 said well for controlling the other valve.

7. An oil still comprising a distilling chamber, an oil inlet pipe at one end of said chamber and an oil well at the other end thereof, an irregular surface over one side 45 of which the oil flows in a film of substantially uniform depth from the inlet to the well, means for admitting a heating agent to the opposite side of said irregular surface, means for conducting said heating 50 agent in a direction opposite to the flow of the oil, and means for controlling the heating agent by the temperature of the distilled vapors.

8. An oil still comprising a distilling 55 chamber, an oil inlet pipe at one end of said chamber and an oil well at the other end thereof, an irregular surface over one side of which the oil flows in a film of substantially uniform depth from the inlet to the well, means for admitting a heating agent to the opposite side of said irregular surface, means for conducting said heating 60 agent in a direction opposite to the flow of the oil, means for controlling the heating agent by the temperature of the distilled 65

vapors, and means for controlling the admission of oil to the chamber by the temperature of the oil.

9. An oil still comprising a distilling chamber, an oil inlet pipe at one end of said chamber and an oil well at the other end thereof, an irregular surface over one side of which the oil flows in a film of substantially uniform depth from the inlet to the well, means for admitting a heating agent 70 to the opposite side of said irregular surface, means for conducting said heating agent in a direction opposite to the flow of the oil, means for controlling the heating agent by the temperature of the distilled 75 vapors, means for controlling the admission of oil to the chamber by the temperature of the oil, and separate means for controlling admission of oil by the amount of oil in 80 said chamber.

10. A process of distilling hydrocarbon oil which comprises passing a film of the oil over a steam heated irregular surface while maintaining substantially uniformity of depth throughout, regulating the admission 90 of oil to said surface by the depth of oil at the outlet, and also by the temperature of the oil at said outlet, and regulating the admission of steam to said surface by the temperature of the distilled 95 vapors.

11. A process of distilling hydrocarbon oil which comprises passing a film of the oil over an irregular surface, passing steam over the opposite side of said surface, regulating the admission of oil to said surface 100 by the depth of oil at the outlet and also by the temperature of oil at said outlet, and regulating the admission of steam to said surface by the temperature of the distilled vapors.

12. A process of distilling hydrocarbon oil which comprises passing a film of oil over one side of an irregular surface in one direction, passing a heating agent over the opposite side of said surface in the opposite direction, regulating the admission of oil to said surface by the temperature of the oil, and regulating the admission of the heating agent to said surface by the temperature of the distilled 110 vapors.

13. A process of distilling hydrocarbon oil which comprises passing a film of oil over one side of an irregular surface in one direction, passing a heating agent over the opposite side of said surface in the opposite direction, regulating the admission of oil to said surface by the temperature of the oil, regulating the admission of the heating agent to said surface by the temperature of the distilled vapors, and preheating said oil 120 before admission to said surface.

In testimony whereof, I have hereunto subscribed my name.

JAMES T. FENTON.
